UNITED STATES PATENT OFFICE.

LEONARD M. RANDOLPH, OF NEWARK, NEW JERSEY, ASSIGNOR TO ESSEX COMPANY, OF NEWARK, NEW JERSEY, A CORPORATION OF NEW JERSEY.

THIRD-RAIL INSULATOR.

No. 922,951.

Specification of Letters Patent.

Patented May 25, 1909.

Application filed May 2, 1907. Serial No. 371,400.

To all whom it may concern:

Be it known that I, LEONARD M. RANDOLPH, a citizen of the United States, and a resident of the city of Newark, in the county 5 of Essex and State of New Jersey, have invented certain new and useful Improvements in Third-Rail Insulators, of which the following is a specification, reference being had to the accompanying drawings, forming a part 10 hereof.

The object of this invention is to provide a third-rail insulator which can be manufactured cheaply from materials usually kept in stock, that is, from materials which for the 15 most part do not have to be made to order, and which can be conveniently assembled and installed.

The invention will be more fully explained in connection with the accompanying drawings in which it is illustrated and in which, 20

Figure 1 is a view in elevation, upon a plane transverse to the direction of the rail, the rail being indicated in dotted lines, and, Fig. 2 is a similar view upon a plane at right 25 angles to the plane of Fig. 1.

The improved insulator comprises essentially three parts, a base *a* which is formed of channel iron, a rail support *b* which is formed of a portion of an I-beam, and a connecting 30 piece of insulating material *c* between the channel iron base and I-beam rail support. The insulator or insulating material *c* is preferably shaped like the frustum of a cone having two flat portions however, which fit 35 against the sides of the channel iron base and prevent the insulator from twisting. It is preferably loosely secured to the base by means of a lug *d* upon the base which engages a corresponding hole in the bottom of the insulator. The I-beam support *b* is of a suitable 40 size to receive and accommodate the rail and is loosely held upon the top of the insulating material *c* by means of a lug *f* upon said support which extends down into the insulating material, whereby the support *b* is 45 capable of relative movement in a vertical direction and of rotation in a horizontal plane with respect to the insulator *c*. In order to

help maintain the rail in its position within the support *b*, one of the flanges of the support, as the flange *e*, is preferably bent over so as to more or less engage the rail. The corresponding flange on the other side is also slightly curved. The rail is inserted by first placing the base flange of the rail within the 55 flange *e* and then bringing the other side down within the flange of the support *b* on the other side.

I claim as my invention:—

1. A third-rail insulator comprising a short 60 section of channel iron, a short section of an I-beam, and insulating material between said sections.

2. A third-rail insulator comprising a short 65 section of channel iron for a base, a short section of an I-beam for a rail support, and insulating material between the base and the support.

3. A third-rail insulator comprising a short 70 section of channel iron for a base, a short section of an I-beam for a rail support, and insulating material between them and to which they are loosely connected.

4. A third-rail insulator comprising a short 75 section of channel iron for a base, an insulator in the shape of a frustum of a cone upon the base, and a short section of an I-beam for a rail support loosely mounted upon the insulator.

5. A third-rail insulator comprising a short 80 section of channel iron for a base, a short section of an I-beam for a rail support, both of which sections are provided with a lug, and an insulator between said base and support in which the lugs rest. 85

6. A third-rail insulator comprising a channel 90 iron base, an insulator upon the base, and an I-beam rail support upon the insulator, one of the flanges of the support being bent over to secure the rail.

This specification signed and witnessed this 29th day of April, 1907.

LEONARD M. RANDOLPH.
